UNITED STATES PATENT OFFICE.

WILLIAM H. ROYAL AND JAMES PRENDERGAST, OF FRANKFORD,
PENNSYLVANIA.

SHUTTLE-BOX LOCK FOR LOOMS.

SPECIFICATION forming part of Letters Patent No. 783,224, dated February 21, 1905.

Application filed December 31, 1903. Serial No. 187,276.

To all whom it may concern:

Be it known that we, WILLIAM H. ROYAL and JAMES PRENDERGAST, citizens of the United States, residing at Frankford, county of Philadelphia, and State of Pennsylvania, have invented a certain new and useful Improvement in Shuttle-Box Locks for Looms, of which the following is a specification.

Our invention relates to a new and useful improvement in shuttle-box locks for looms, and has for its object to provide means for automatically locking the shuttle-box against movement while the picker-stick operates to shoot the shuttle along the race in the lathe and to automatically unlock the shuttle-box to allow the same to be moved while the shed is being formed.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a side elevation of my improvement; Fig. 2, a plan view of the same; Fig. 3, an enlarged detail view of the curved arm to which the adjustable studs are secured.

A represents the frame of the loom. B is the rod, which extends upward to the shuttle-box for shifting the same. C is the lever pivoted at the point C', which operates the shifting-rod B. Upon these parts we do not claim any invention, as they are old in looms. Our invention consists in securing to the end of the lever C a curved arm or strip D, which is formed concentric with the pivotal point C'. This curved arm D has formed through it at intervals slots E, through which extend bolts F, secured to the studs G. Nuts H, threaded upon the other end of the bolts upon the opposite side of the arm D, serve to secure the studs G in place. There are just twice as many studs as there are shuttles in the shuttle-box.

On the frame A is secured a bell-bracket a. I is a flat blade pivoted to the end of the

lower arm of the bracket a at the point J and extends at right angles with the strip D. The forward end of this blade in close proximity to the studs G passes through a slotted guide K, secured to the framework. The other end of the blade upon the opposite side of the pivot J is connected to a rod L, which rod is adapted to be reciprocated at predetermined times by any suitable mechanism connected to the loom. The mechanism shown in the drawings consists of a cam M, operating upon a roller N, secured upon the rod L. This cam is designed to reciprocate the rod in one direction and the spring O is adapted to move the blade I in the opposite direction. The spring O is secured at one end near the end of the upper arm of the bracket a and at its opposite end to an end of the blade I. As the forward end of the blade I is moved or oscillated it is adapted to move between certain studs G and then be moved out of engagement with said studs. For the purpose of locking and unlocking the bar D the blade I is forced in between the studs by means of the spring O after the lever C is moved to shift the shuttle-box to bring the proper shuttle in position for the picker-stick to shoot said shuttle along the race, and this will hold the shuttle-box steady against any movement while the shuttle is being thrown; but as soon as the shuttle has passed to the other end of the race the cam M will have moved so as to act upon the blade I to move said blade out of engagement with the studs and therefore allow the lever C to move so as to bring the next proper shuttle in position while the shed is being formed.

The studs G, by passing through the slots E in the arm D, may be adjusted either one way or the other, so that the knife-blade I in passing between the studs will be sure to bring the proper shuttle in exact alinement with the shuttle-race and hold it in such position while the shuttle is thrown.

Of course we do not wish to be limited to the exact construction here shown, as slight modifications could be made without departing from the spirit of our invention.

Having thus fully described our invention, what we claim as new and useful is—

In combination with a frame having a bell-

bracket secured thereto, a supporting-rod for a shuttle-box, a pivoted lever for moving said rod, a curved strip formed on an end of the lever and having slots, removable studs secured in the slots and projecting therefrom, a blade pivoted intermediate its length to the lower arm of the bell-bracket and extending at right angles to the curved strip, one end of the blade being adapted to lie normally between certain of the studs, a movable connection at the opposite end of the blade to draw the blade from its normal position, a spring connected at one end to the upper arm of the bell-bracket and at its opposite end to an end

of the blade, said spring being adapted to return the blade to its normal position and a slotted plate secured to the frame, the pivoted blade passing through said slot, said plate acting as a guide for the blade in its movements. 15

20 In testimony whereof we have hereunto affixed our signatures in the presence of two subscribing witnesses.
